UNITED STATES PATENT OFFICE.

SHOKICHI ISHII, OF TOKYO, JAPAN.

TYPEWRITER.

Application filed November 26, 1926. Serial No. 150,982.

This invention relates to an improvement in typewriters and more particularly to a typebar and arrangement thereof, in which the typebar is provided with a head polygonal in cross section adapted to carry several different types on the surfaces thereof and is rotatable and telescopic, so that any types desired may be set in a position to strike against the platen at the proper typewriting position, particulars of which will hereinafter appear; and the invention has for its object to provide an improved typewriter capable of being provided with several alphabets in different languages in a single machine and to lessen number of keys, which is very convenient to the user and simple to construct.

Referring to the accompanying drawings:—

Figure 1 is a general plan view showing mainly parts of the typebar and arrangement thereof according to the present invention.

Figure 2 is a front view of Figure 1.

Figure 3 is a side view of an arrangement of typebar and supporting member thereof.

Figure 4 is a plan view of Figure 3.

Figure 5 is a view partly in section showing connection of the typebar with sleeve thereof, and

Figure 6 is a vertical sectional view of Figure 3 on the line A—B.

This invention relates to an improvement in typewriters, more particularly consists in the features of constructions and arrangement of typebars in typewriter, in which the typebar may be provided with a number of different types, and so that any desired one of these types may be positioned to strike against a proper point of the platen by imparting rotation and telescopic motion thereto. A typewriter as a complete set must, of course, be provided with a platen, carriage, spacer, paper feed, ribbon feed, back spacer and other necessary mechanisms, means and arrangements as well known, and these are not included in the present invention and may be of any suitable constructions. Now, the invention itself will, therefore, be shown and described, omitting the description in connection with the other parts.

The typebar according to this invention consists of a head 1 polygonal in cross section, a stock thereof 2 and a supporting neck 4 extending from the head 1 and having a knob 5 serving as a stop. The typebar head

1 is formed with several types on each face thereof, the type-faces being, of course suitably curved to conform with curvature at the striking point of a platen.

The typebar is inserted into a sleeve 3 by its stock 2. The sleeve 3 is of tubular shape with a closed end, from which end extends a stem 6 which is rotatably mounted in a bearer member 7, which is pivotally mounted in the upper part of each of a number of grooves formed in rows in the upper side of a support member 8, which upper side is of arch shape. At the end extending outwardly from the bearer member 7 is fixed a counter weight 9. The bearer member 7 is provided with an arm 10 whereby the bearer member 7 and accordingly the typebar may be swung towards the platen. To the outer end of the arm 10 is pivotally connected a lever 11, the other end of which is bent upward and connected with a key 12, as is well known.

On the surface of the sleeve 3 are formed two spiral grooves 13, and each sleeve is mounted in one of a number of grooves provided in rows on the upper side of an actuating member 14, which side is formed in arch shape as in the support member 8, the grooves 13 being engaged by pins 15 provided in opposite sides of the groove 14.

To permit removal of the sleeve 3 from the groove of the actuating member 14 when the typebar swings toward the platen, the sleeve 3 is grooved circumferentially from each of the points in the spiral grooves 13 where the pins 15 rest when the typebar lies at the proper swinging position, so as to form a path for the pins 15, as shown at 16.

The actuating member 14 is provided with operating levers 26, at the outer end of which are secured handles 23, for purposes to move forwards or backwards the actuating member 14 to rotate the typebar, so as to direct any desired typeface towards the platen, but this may be preferably replaced by any suitable means, such as a shift-key as well-known.

The fore end of the typebar is supported on a shifting member 25, the supporting neck 4 at the fore end of the head 1 of the typebar being mounted on the grooves provided on the shifting member. The shifting member is connected to handles 24 and may be moved forward or backwards by the same, whereby the typebar may be moved forwards or backwards to bring any desired

types to the proper position for typewriting. In order that the typebar may be telescopic in the sleeve 3 and rotatable with the sleeve, the stock 2 of the typebar is provided with a guide groove 17, whereinto a pin 18 is inserted through the sleeve 3.

The length of the guide groove may be made as to limit the forward and backward movement of the typebar. For the purpose 10 of holding the typebar at its proper typewriting position in the sleeve 3, the stock 2 of the typebar is provided with a leaf spring 19 with a button 21 on the free end thereof, which button engages with hole 22

15 at the sleeve 3 and serves as a stop. A cavity 20 is formed at the stock 2 so that the spring 19 may bend backwards to get out from the hole 22 when the typebar is forced forwards or backwards.

20 In operation, any desired type may be struck against the platen by rotating the typebar by the handles 23, and moving forwards or backwards the same by the handles 24, and moreover by means of the key 25 12, as seen from the above description.

The invention is not limited to the constructional form as above described and shown in the drawings, and various modifications and changes may be made without departing from the spirit and scope of the 30 said invention.

Having now particularly described and ascertained the nature of the said invention, and in what manner the same is to be performed, I declare that what I claim is:—

1. In typewriters, a typebar formed in sections, one being in the form of a sleeve, surrounding the other in telescopic but non-rotative relation, said sections being provided, the one with a series of holes arranged 40 at intervals longitudinally, and the other with a spring detent engageable selectively in holes for determining selective length values for said typebar, means upon which 45 said typebar is swingably mounted and shift-

ing means engageable with said typebar when it assumes its position of repose relative to its swinging movement, for drawing out said other section to one of the selective positions determined by said holes and 50 detent.

2. In typewriters, a typebar formed of relatively extensible sections, the one of which carries type on different sides thereof, means for rotating said sections to bring 55 the desired type to printing relation, including a sleeve, the same comprising the other section and non-rotatable with respect to the first section, said sleeve being provided with spiral grooves and an actuating 60 member for rotating said sections movable axially of said sleeve and having pins fitting said grooves.

3. In typewriters, a typebar formed in sections, one being in the form of a sleeve 65 surrounding the other in telescopic but non-rotative relation, said sections being provided, the one with a series of holes arranged at intervals longitudinally, and the other with a spring detent engageable selectively 70 in said holes for determining selective length values for said typebar, one of said sections carrying type on different sides thereof, said sections being rotatable to bring the desired type into printing relation, said sleeve being provided with spiral grooves, and an actuating member for rotating said sections, movable axially of said sleeve and having pins fitting said grooves, means upon which 75 said typebar is swingably mounted, and shifting means engageable with said typebar when it assumes a position of repose relative to its swinging movement for drawing out the type carrying section to one of the selective positions determined by said 80 holes and detent.

In testimony whereof I have signed my name to this specification.

SHOKICHI ISHII.
